J. PÉRINET

Des. 171,824

COMBINED PERFUME BOTTLE AND CONTAINER THEREFOR

Filed Nov. 18, 1952

FIG. 3.

FIG. 2

UNITED STATES PATENT OFFICE

171,824

COMBINED PERFUME BOTTLE AND CONTAINER THEREFORJean Périnet, Boulogne-sur-Seine, France, assignor to Societe a Responsabilite Limitee Dite:
Marquay, Paris, France, a corporation of France

Application November 18, 1952, Serial No. 22,332

Term of patent 14 years

(Cl. D58—9)

To all whom it may concern:

Be it known that Jean Périnet, a citizen of the French Republic, residing at Boulogne-sur-Seine, Department of the Seine, State of France, 2 Place des Ecoles, has invented a new, original and ornamental Design for a Combined Perfume Bottle and Container Therefor, of which the following is a specification, reference being had to the accompanying drawing, forming part thereof.

Fig. 1 is a front view of a combined perfume bottle and container therefor showing my new design;

Fig. 2 is a rear view thereof, and

Fig. 3 is a side elevation thereof.

I claim:

The ornamental design for a combined perfume bottle and container therefor, as shown.

JEAN PÉRINET.
